Patented Nov. 26, 1974

233,798

TELEVISION ENLARGEMENT- DISPLAY UNIT

Alphonse P. Cinque, 65 Earle Ave.,
Lynbrook, N.Y. 11563

Filed Jan. 2, 1973, Ser. No. 320,131

Term of patent 14 years

Int. Cl. D16—03

U.S. Cl. D61—1 Q

FIG. 1

FIG. 2

FIG. 3

FIG. 4

FIG. 5

FIG. 6

FIG. 1 is a left front perspective view of a television enlargement-display unit showing my new design;

FIG. 2 is a left side elevational view thereof, the right side being a mirror image thereto;

FIG. 3 is a front elevational view thereof;

FIG. 4 is a top plan view thereof;

FIG. 5 is a rear elevational view thereof;

FIG. 6 is a bottom plan view thereof.

I claim:

The ornamental design for a television enlargement-display unit, substantially as shown and described.
